UNITED STATES PATENT OFFICE.

JOHN E. RILLING, OF MILWAUKEE, WISCONSIN.

MATTRESS.

1,153,644.

Specification of Letters Patent. Patented Sept. 14, 1915.

Application filed November 7, 1914. Serial No. 870,724.

To all whom it may concern:

Be it known that I, JOHN E. RILLING, a citizen of the United States, and resident of Milwaukee, in the county of Milwaukee and 5 State of Wisconsin, have invented new and useful Improvements in Mattresses, of which the following is a description, reference being had to the accompanying drawings, which are a part of this specification.

10 The invention relates to mattresses.

The invention designs more particularly to provide a spring mattress made up of a plurality of sections.

15 The invention further designs to provide a spring mattress made up of a plurality of sections and means for connecting adjacent sections together so as to form a unitary structure.

20 Heretofore mattresses have been made of a plurality of sections and means have been provided for connecting adjacent sections together but these constructions are objectionable because the sections acted independently and not as a unit. To obviate this 25 difficulty means have been provided for not only connecting the adjacent sections of the mattress together but also connecting the springs adjacent the edges of adjacent mattress sections together so that a unitary mattress construction will result.

30 The invention further designs to provide a new and improved form of mattress construction.

35 The invention consists in the several features hereinafter set forth and more particularly defined by claims at the conclusion hereof.

40 In the drawings Figure 1 is a perspective view of the mattress embodying the invention; Fig. 2 is a section taken on line 2—2 of Fig. 1; Fig. 3 is a section taken on line 3—3 of Fig. 2; Fig. 4 is a section taken on line 4—4 of Fig. 2.

45 The separatable mattress consists of a plurality of mattress sections 5 and means for securing them together to produce a unitary mattress. Each of these sections comprise a plurality of springs 6 whose intermediate convolutions are straightened so that links 50 7 connecting adjacent springs will exert a

straight pull upon the springs and the springs adjacent the outer edge of the section are connected intermediate their ends to a surrounding frame 8 having a reinforcing cross bar 9. Flexible coverings 10 are 55 secured to the upper and lower portions of the springs 6 by stitching 11 and an outer covering 12 surrounds each section.

The means for securing the mattress sections together comprises eyelets 13 inserted 60 adjacent the edge 14 of adjacent mattress sections through which suitable lacing 15 is inserted to secure the mattress sections together. These eyelets 13 are inserted adjacent the edges 14 of the outer covering 12 65 passing through the upper and lower sides of said covering respectively and through an overlapped portion 16 of said cover and at the same time passing within the upper and lower convolutions of the springs 6 respectively with the result that when the sections are secured together by a suitable means such as lacing 15 there will be a direct coaction between the sections and a unitary mattress will be produced as the lacing secures not only the edges of the adjacent 70 75 separate sections together but also the springs in each section adjacent the edges.

The invention thus exemplifies a mattress made up of a plurality of separate spring 80 mattress sections connected together by means which connect the springs of adjacent sections to produce a unitary mattress.

The invention is not to be restricted to the details of construction herein set forth but 85 may be varied so as to be within the scope of appended claims.

What I claim as my invention is:—

1. A separable mattress comprising a plurality of mattress sections, each of said sections comprising a plurality of springs joined together and upper and lower flexible coverings secured to the upper and lower portions of said springs, eyelets passing through said coverings and through the 90 springs adjacent the side edges of each section, and means passing through the eyelets for securing adjacent sections together to produce a unitary spring mattress.

2. A mattress comprising a plurality of 100

separate mattress sections, each of said sections comprising a plurality of springs and flexible coverings secured to said springs, and means passing through said coverings and through the springs adjacent the bottom and top edges of the sides of adjacent sections to detachably connect said sections together to produce a unitary spring mattress.

In testimony whereof, I affix my signature, in presence of two witnesses.

JOHN E. RILLING.
